UNITED STATES PATENT OFFICE.

SAMUEL D. BUTTERWORTH, OF LANSING, MICHIGAN.

AUXILIARY REINFORCEMENT FOR REINFORCED CONCRETE CONSTRUCTION.

Application filed August 16, 1924. Serial No. 732,385.

This invention relates to a reenforcing member for securing concrete to the under side of I-beams. The underwriters and most building codes require the contractor to 5 cover an I-beam with at least two inches of concrete for fire protection. This means that the I-beam or other steel section used in concrete beam construction must be entirely surrounded by concrete so that the outside 10 surface of the concrete is at least two inches from any point of the I-beam. However, great difficulty has been experienced in holding 15 the concrete to the bottom of the I-beam, as the bottom of the beam is smooth and the concrete thereover is suspended merely by the two inches of concrete at the side. There is great danger of this portion of the 20 concrete beam peeling off and falling after the building has been constructed, which might cause serious damage and loss of life.

Many devices have been devised for holding this concrete to the I-beam, but as far as I know, these devices have not proven entirely satisfactory. The devices on the market 25 are of such a construction that they will slip and as these reenforcing devices need to be spaced accurately, it is quite necessary that they should stay put. It has been the custom to wrap these I-beams with a wire 30 or steel coil, locating these wires at approximately one foot apart. But during the process of building the box frame about the I-beam in preparation for pouring the concrete, these wire coils are easily misplaced 35 and there is a great chance of them all sliding towards one end of the beam, thereby leaving a great section of the beam without this necessary reenforcement. With 40 these devices, however, it is necessary to also provide spacers for correctly positioning and holding the mold box in correct relation with respect to the I-beam, so that the minimum allowance of two inches of concrete may be maintained.

The object of my invention is to overcome these numerous difficulties and I provide a reenforcing member which may be clamped to the I-beam in such a way that the same will not slip and will remain put. In addition, my construction includes means 45 for spacing the mold box from the I-beam, thereby performing a double function not found in the devices in the prior art. In addition, my device may be formed of a stamping 50 and manufactured at a very low cost.

In fact the same may be sold at less cost than the devices now on the market and they are also labor saving devices since they are more readily and quickly assembled to the I-beam in preparation for pouring the concrete. 60

In the drawings:

Fig. 1 is a perspective view of an I-beam, showing my reenforcing clamps secured thereto. 65

Fig. 2 is a perspective of one of my clamps.

Fig. 3 is a section through an I-beam, showing the clamp about to be put on.

Fig. 4 is a side elevation of the I-beam, 70 showing my reenforcing clamp secured thereon.

Fig. 5 is a vertical section through a concrete beam reenforced by an I-beam section and showing my reenforcing clamp secured thereon. 75

Fig. 6 is a sectional view through an I-beam section used for a column, showing my reenforcing members secured thereto.

Fig. 7 is a perspective view of my clamps 80 showing the struck out transverse reenforcing tongues.

Fig. 8 is a detail of the blank used for forming the clamping members.

a designates an I-beam that is used for 85 reenforcing a concrete beam, the concrete designated b, as shown in Fig. 5, to hold that portion of the concrete b designated b¹ in place, and to prevent the same from falling off after the concrete has set, I provide 90 a reenforcing device which is adapted to be secured to this I-beam as will now be described.

I form a special fixture or flange clamp of sheet metal formed from a stamping in such a way as to provide a spring clip c with the inwardly extending spring gripping jaws or fingers d. It is also provided with a depending leg e, which serves as a spacer for locating the bottom of the mold trough in correct position with respect to the I-beam. This special fixture or clamp is also provided with a side extension f, which serves as a spacer for the sides of the mold box. The depending leg carried by the fixture is provided with an inwardly struck out tongue g. 100

This fixture may be forced onto the bottom flange of the I-beam, as shown in Figs. 110 3 and 5, the spring gripping fingers or jaws

d engaging the upper surface of this flange, and as the same is forced on, these gripping members will tightly grip and bite into the I-beam flange and so securely grip the I-beam that there is no tendency for the clamp to slip or become misplaced. These clamping fixtures are secured on opposite sides of the I-beam, as shown in Fig. 5, the tongue *g* bridging the gap beneath the I-beam to provide a transverse reenforcement for the concrete. A steel rod *h* may be laid thereon, as shown in Fig. 4, when a broad I-beam is used to provide a stronger transverse reenforcement for tying the concrete designated *b*¹ to the central reenforcing member of the I-beam.

These fixtures are normally positioned about one foot apart but sometimes they are positioned at a greater distance and therefore to provide the necessary reenforcement for the intervening space between each pair of fixtures, a reenforcing rod *i* is laid on top of the rods *h* and is positioned longitudinally of the I-beam. These reenforcing rods may be secured together where they cross by means of the wire loop *j*. However, I want it understood that I am not bound to always use this longitudinally running reenforcing member *i*, as there are occasions when it is not necessary.

After these fixtures have been secured to the I-beam, the box frame *k* is secured about the I-beam, the spacers *f* and *e* locating the sides and the bottom respectively of the mould box in the correct position. The concrete is now poured and the same flows around these reenforcing fixtures and when the concrete is set all parts of the auxiliary reenforcing fixture are embedded in the concrete, thus securely tying that portion of the concrete beam designated *b*¹ to the central reenforcing steel I-beam.

In Fig. 6 I show how my reenforcing fixture is adapted to be used in column construction. In column construction there is the same requirement as to the amount of concrete around the I-beam, and to provide means for reenforcing the concrete and for spacing the column mould with respect to the I-beam, I place a number of my fixtures on both flanges of the I-beam section, as clearly shown in Fig. 6. Thus, when the concrete is poured, the same is sufficiently reenforced and prevents that portion of the concrete adjacent the outside flanges of the I-beam section from peeling off and falling after the concrete is set.

Fig. 8 shows a blank which is cut transversely as at 10; the flaps 11 being folded over on the dotted lines 12 to form the leg *e*. The sheet metal blank is also cut as at 13, the outer portions of the blank being curled back to form the spring clips *c* and the jaws or fingers *d*.

In some of the claims we have referred

to the web of the clamp underlying the flange and the spring fingers as gripping the top of the flange. These terms are simply used relatively as a clear means of designating the parts. Of course, if the auxiliary reenforcement be used on a column, strictly speaking, the flange has no upper and lower surface, but the flange can be read with this explanation in view.

What I claim is:

1. An auxiliary reenforcement for tying or supporting concrete on a heavy central reenforcement member or core for concrete beams or columns, having in combination with a central flanged reenforcing core of 80 a plurality of sheet metal flange clamps which may be secured to the central reenforcing core by springing the sheet metal thereon, a transverse reenforcing member, said clamp further provided with means for supporting said transverse reenforcement for tying the surrounding concrete to the central core.

2. A device for the purpose specified, comprising a sheet metal member formed to provide a relatively wide spring gripping jaw, a laterally extending mould wall spacer and a combined mould wall spacer and hanger substantially at right angles thereto, the said combined spacer and hanger serving to support auxiliary reenforcements.

3. A device for the purpose specified, comprising a sheet metal flange clamp formed from a single sheet of metal bent to form a pair of relatively wide turned over spring fingers engaging the top of one flange of a reenforcing member, and provided with a depending portion having lateral projections for tying the surrounding concrete to the reenforcing member at the center.

4. A device for the purpose specified, comprising a sheet metal flange formed into a web to underlie a flange of a center reenforcement and provided with turned up 110 spring fingers engaging the top of the flange, said flange clamp further provided with a turned down leg member having a struck out tongue, said leg member and tongue serving to tie the concrete to the center reenforcement.

5. An auxiliary reenforcement for tying and supporting concrete on a heavy central reenforcement member or core for concrete beams or columns, having in combination with the central core, a plurality of 120 independent sheet metal flange clamps which may be secured to the flanges of the central reenforcing core by springing the sheet metal thereon, tying members, said clamps having integral mould wall spacers 125 and means for supporting said tying members for tying the surrounding concrete to the central core.

6. A reenforcement structure of the class described, comprising a sheet metal mem-

ber provided with a web arranged to underlie one flange of a central reenforcement, and provided with turned up spring fingers engaging the top of the flange, transverse reenforcing means, said sheet metal member being further provided with a projecting member for supporting said transverse

means and additional reenforcing means supported by said transverse reenforcing means.

In testimony whereof I have affixed my signature.

SAMUEL D. BUTTERWORTH.
